UNITED STATES PATENT OFFICE.

JOHN O. FRYER, OF LOWELL, MASSACHUSETTS.

JACQUARD MECHANISM FOR LOOMS.

SPECIFICATION forming part of Letters Patent No. 257,690, dated May 9, 1882.

Application filed July 8, 1880. (No model.)

To all whom it may concern:

Be it known that I, JOHN O. FRYER, of Lowell, in the county of Middlesex and Commonwealth of Massachusetts, have invented 5 certain new and useful Improvements in Jacquard Mechanisms for Looms, of which the following is a specification.

My invention relates to what is called the "jacquard" of a loom, meaning that mechanism which (independently of the harnesses which dispose the warps for the ground of the fabric) in weaving figured goods causes those threads which produce the figure to rise and fall at the proper times, and my said invention 15 is intended exclusively for looms which form a figure on one face only of the fabric.

The object of my invention is to revolve the pattern-prism but once in two picks, and thus to make a given figure (on one face of the fabric) with only half the pattern-cards required by the jacquards commonly used, thus also avoiding to a great extent the danger of mis-picks and the trouble of punching half the cards and the weight of half the cards. This 25 I accomplish by causing the prism to be rotated by the falling of the griff and by causing the griff to fall only once in two picks, or, more properly, at every other pick—that is, by the combination, with the griff provided with 30 a piece slotted outward and upward, and mechanism for causing said griff to fall at every other pick of the loom, of the prism and mechanism for causing said prism to revolve at the falling of said griff; or, more specifically, in the 35 combination of the griff provided with a piece slotted upward and outward, the griff-lever and its connecting-rods, the counter-shaft provided with a crank and a gear, the main shaft, also provided with a gear, the former 40 gear having twice as many teeth as the latter gear and caused to revolve by the latter, the prism provided with pins, and the pawl or hook pivoted to the frame of the jacquard.

The accompanying drawings, on three sheets, 45 represent my invention. Figures 1 and 4 are front elevations of my jacquard, the griff being up in Fig. 1 and down in Fig. 4. Figs. 2 and 5 are end elevations of the same, the griff being up in Fig. 2 and down in Fig. 5, the latter figure also showing the main shaft and the counter-shaft. Fig. 3 is an end elevation 50 of the prism, with the swinging frame, (a part of

the latter being broken away to show the T-bar bearing on the end of the prism,) the pawl and spring, and part of the jacquard-frame. 55 Fig. 6 is a horizontal section of the jacquard just above the griff, the griff being up. Figs. 7 and 8 are side elevations of a single hook and its needle, with the prism and the griff in section. In both figures the griff is up, but 60 the position of the hook and griff when both are down is shown by dotted lines in Fig. 7, and in this figure the needle is in a position to allow the hook to fall with the griff. In Fig. 8 the needle prevents the hook from falling with the griff when the griff drops to the 65 position shown by the dotted lines.

A is the frame of the jacquard, and may be supported on the loom-frame or secured to the ceiling of the room in which the loom is placed. 70

B is the vertically-reciprocating griff.

C is the griff-lever, being in effect a forked lever, but usually made of an arm secured to a shaft turning in the frame A, projecting on each side of said frame, and stiffly secured to 75 two parallel pieces or arms, one on each side of the frame, as shown in Figs. 1 and 6, said shaft and three arms forming the lever C.

The lever C is connected by rods D to the griff, and by another rod, E, to the crank or 80 eccentric, which, through said lever and connecting-rods, raises and lowers the griff.

F is the pattern-prism, secured to the lower part of the swinging frame G.

H is a pawl pivoted to the frame and hooked 85 on the upper side, which, catching on pins I, driven into the end of the prism at its corners, rotates the prism.

Various other devices, (well known,) all of which depend for their operation upon the 90 swinging of the frame G, may be substituted for the pawl and pins.

All of the parts above designated by letters of reference are of the usual construction, and need no further description. 95

The rod E at its lower end (instead of being connected to a crank on the main shaft K, as is usually done) is connected with a crank, X, or its equivalent, on a counter-shaft, L. This counter-shaft is driven by a gear, M, secured 100 to it and containing a given number of teeth and taking into a gear, N, the latter gear having only half as many teeth as the gear M, and being secured to said main shaft K. Now,

the main shaft or "crank-shaft," as it is commonly called, operates the lay and revolves necessarily once for every pick; but the counter-shaft revolves only half as fast as the main shaft, and therefore, by means of the connecting-rod E and griff-lever and rods D, raises the griff at one pick and causes said griff to fall at the next pick.

Raising the griff swings the prism F in toward the needles T, because a piece, O, rigidly secured to or made in one piece with the griff is slotted at P upward and outward from the griff, as shown in Figs. 2 and 5, and the end of the prism-shaft reaches into the slot P, the prism, as already stated, having its journals in the swinging frame G. Lowering the griff of course swings the prism in the other direction, the pins I catching in the pawl H and causing the prism to make a quarter of a revolution as it swings out, the pins I slipping over the beveled free end of the pawl as the prism swings in. The prism is usually prevented from making more than quarter of a revolution by a piece or bar, Y, called the "T," in shape like an inverted T, said bar being pressed down upon the end of the prism by a spring, Y'. The lifting of the griff also raises the vertical hooks Q by the shoulders R on the shanks of said hooks, these hooks being of sheet metal and running through slots in horizontal bars A' A'', secured to said frame A, so that the hooks have no motion except in the direction of their length, whereas ordinarily the hooks swing from their lower ends, and being hooked at the top, as well as at the bottom, they are caught by the griff only when their hooks are swung over the griff.

The shanks of the hooks Q are passed through vertical slots V in the horizontal needles T, (see Figs. 7 and 8,) and are provided with other shoulders, R', placed at such a height on the shank that when the hooks are lifted by the griff said last-named shoulders R' rise just above the tops of the needles T.

The needles T are pushed out toward the prism by spiral springs U, and the points of the needles enter perforations in the cards W, or are crowded back by being struck by the unperforated parts of the card very much in the usual manner; but the needles, instead of being of round wire of uniform diameter, looped to receive the shanks of round hooks, are slotted to receive the flat hooks above described, and, instead of being bent to form bearings for the springs, are larger than the springs in di-

ameter and turned down to enter the springs and to form shoulders for the springs to bear against, and are also turned down small to enter the pattern-cards W. The needles T are supported in parts A³ A⁴ of the frame A, the ends of said needles passing through said parts A³ A⁴, as shown, so that said needles are limited to a longitudinal motion.

It is evident that when the hooks are first lifted by the griff, which every time it rises lifts all the hooks not already up, the needles will be pushed by their springs toward the prism until the needles (or, at least, such of them as are not stopped by the pattern-card) are pushed under the shoulders R', and that the hooks whose shoulders overhang the needles will be supported by said needles until their respective needles are forced back by being struck by the unperforated spaces of the pattern-cards W in the usual manner, so that the hooks do not all fall at every fall of the griff, but remain up until the pattern requires them to fall.

When an ordinary Jacquard loom is forming a figure on one face only of the fabric every alternate card must be punched "full"—that is, with a hole for each needle—for the hooks must all rise at every other pick or there will be a line of color on the reverse of the fabric. I dispense with every other card—that is, with the full cards—by having my prism revolve only when the griff falls—that is, once in two picks.

I claim as my invention—

1. The combination, with the griff B, piece O, slotted upward and outward, and mechanism for causing said griff to fall at every other pick of the loom, of the prism F and mechanism for causing said prism to revolve at the falling of said griff, as and for the purpose specified.

2. The combination of the griff B, piece O, slotted at P upward and outward, the griff-lever C, and its connecting-rods D E, the counter-shaft I, provided with a crank, X, and a gear, M, the main shaft K, also provided with a gear, N, the former gear, M, having twice as many teeth as the latter gear, N, and caused to revolve by the latter, the prism F, provided with pins I, and the pawl or hook H, as and for the purpose specified.

JOHN O. FRYER.
